UNITED STATES PATENT OFFICE

WILLIAM G. SHELTON, OF ST. LOUIS, MISSOURI

DESIGN FOR A HAIR-WAVING-MACHINE CABINET

Application filed December 26, 1930. Serial No. 38,121. Term of patent 7 years.

To all whom it may concern:

Be it known that I, WILLIAM G. SHELTON, a citizen of the United States, residing at the city of St. Louis, State of Missouri, have invented a new, original, and ornamental Design for Hair-Waving-Machine Cabinet, of which the following is a specification, reference being had to the accompanying drawing, forming part thereof.

The drawing is an isometric view of the cabinet.

I claim:

The ornamental design for a hair waving machine cabinet, as shown.

WILLIAM G. SHELTON.
